US00D387072S

United States Patent [19]
Ojanen

[11] **Patent Number:** Des. 387,072

[45] **Date of Patent:** **Dec. 2, 1997

[54] **THREE-FINNED POINT ATTACK MINING
BIT**

4,446,936 5/1984 Sarin et al. 175/420.1
4,527,931 7/1985 Sarin 407/113

[75] Inventor: **Randall W. Ojanen**, Bristol, Tenn.

Primary Examiner—Antoine Duval Davis
Attorney, Agent, or Firm—Dickstein Shapiro Morin & Oshinsky LLP

[73] Assignee: **Rogers Tool Works, Inc.**, Rogers, Ark.

[**] Term: **14 Years**

[57] **CLAIM**

[21] Appl. No.: **58,308**

The ornamental design for a three-finned point-attack mining bit, as shown and described.

[22] Filed: **Jul. 25, 1996**

DESCRIPTION

[51] LOC (6) Cl. **15-09**

FIG. 1 is a top view showing my new design for a three-finned point-attack mining bit;

[52] U.S. Cl. **D15/139**

FIG. 2 is a front view of the bit of FIG. 1 showing one fin fully and the other two fins partially. Full views of the other two fins are identical and have been omitted;

[58] Field of Search D15/138, 139;

FIG. 3 is a back view of the bit of FIG. 1; and,
FIG. 4 is a bottom view of the bit of FIG. 1.

175/57, 420.1, 420.2; 407/113
